UNITED STATES PATENT OFFICE.

WILLIAM ROWAN, OF BELFAST, COUNTY OF ANTRIM, IRELAND.

PISTON.

SPECIFICATION forming part of Letters Patent No. 292,445, dated January 22, 1884.

Application filed September 18, 1883. (No model.) Patented in England February 6, 1883, No. 619.

To all whom it may concern:

Be it known that I, WILLIAM ROWAN, a subject of the Queen of Great Britain and Ireland, residing at Belfast, in the county of Antrim, Ireland, engineer, have invented certain new and useful Improvements in the Construction of Pistons, (for which I have received Letters Patent in Great Britain dated February 6, 1883, No. 649;) and I do hereby declare the following to be a full, clear, and exact description of the invention, such as will enable others skilled in the art to which it appertains to make and use the same.

My invention refers, primarily, to a piston having two packing-rings, which are pressed apart from each other and against the junk-ring and the flange of the body of the piston by an intermediate ring, while the said packing-rings are pressed against the sides of the cylinder by other springs placed on the inside of the said packing-rings. I employ a curved helical spring for pressing the packing-ring apart and outward against the sides of the cylinder, while at the same time its curved middle portion presses against the joint-piece or gullet, holding it steam-tight against the inside of the packing-rings. This helical spring is first bent to the required radius and then, at each end, connected to or inserted in abutment pieces or lugs, which are riveted on or otherwise fixed or formed on a thin ring or hoop, made of steel, or iron, and either wave-shaped or plainly circular. This hoop or ring lies against the inside of the packing-ring, and is nearly of the same depth. The helical spring may be made from a cast-steel tube cut in the lathe to any pitch required to suit the strength of spring required, or it may be made by winding a flat, round, or other rod of steel or other suitable elastic material round a mandrel in the ordinary manner. A mandrel or core is placed inside the helical spring to keep it in form and position when in the piston. The gullet-piece before referred to is preferably made of L-section in the middle.

This description of the improved springs and their action on the packing-rings will be more clearly understood by referring to the

accompanying sheets of drawings, in which 50 the same reference-letters are used in the several figures to denote the same parts.

Figure 1 is a plan of a piston, one-half of which is in section, so as to show one of the packing-rings A with the helical spring B in 55 position, also the hoop or ring C on which the abutments D D are fixed to carry the helical spring B, and receive the pressure therefrom, which pressure is imparted by the hoop to the packing-ring A equally all round its circumference. The joint-piece or gullet E, against which the helical spring B presses, is also shown in position in Figures 1, 2, and 3. Fig. 2 is a side elevation of the same piston, the right half being in section, showing both 65 packing-rings A A in section, with the flat helical spring B B against the joint-pieces E E. In this section, as well as in sections Figs. 3 and 5, the joint-pieces of both packing-rings are shown together for convenience of illustration, but in practice they break joint with each other in the usual manner. In Fig. 3 the helical springs B B are shown of round section and partly housed in the gullets E E, though this housing may be confined to the 70 abutment-pieces, as shown on Fig. 1. The wave-spring F for pressing the packing-rings endwise against the junk-ring and piston-flange faces is shown in Fig. 2 in elevation on the left-hand half of the figure and in section 75 on the right. This spring is also in section in Figs. 3 and 5 in its position between the two packing-rings. In Figs. 2 and 5 the wave-spring is shown as housed, or lying in a recess in the packing-rings, while in Fig. 3 this spring 80 is shown between the two packing-rings without any housing. The packing-ring may be made in either way without affecting the efficiency of the piston.

In cases where a very small space is allowed 90 for the packing-rings, the helical springs may be made to lie close to the packing-rings with only the ring C between. This modification is shown in Figs. 4 and 5, which are, respectively, a part plan and sectional elevation. The 95 joint-piece E in this modification does not project beyond the inner diameter of the packing-ring, and the band which carries the abut-

ments D D is continued round over the cut in the packing-ring until the two ends nearly meet.

The several figures in the sheet of drawings 5 are illustrations of a piston having a junk-ring; but my improvements are also applicable to pistons without junk-rings, such as are in use for locomotives and other engines. In such pistons the packing-rings are sprung over 10 the outer diameter of the piston and put into their respective places by suitable tools, the springs having been previously placed in position. The wave-spring is placed before the second packing-ring is put in, and in this form 15 of piston the wave-spring is not, as in Fig. 2, housed between the packing-rings, but lies on the space between them, as shown in Fig. 3. For gas-motor engines, where the pressure 20 acts on one side only, I may use only one packing-ring A, and no spring F.

I claim—
1. The combination, with a piston having packing-rings A, of the inner ring or spring-hoop, C, and the helical springs B, which expand the packing and press the rings A 25 against the sides of the cylinder, substantially as and for the purpose set forth.

2. The combination, with a piston having packing-rings A, of the inner ring or spring-hoop, C, and the helical springs B, which press 30 the packing-rings A against the sides of the cylinder, and the wave-shaped spring F, placed between the packing-rings and serving to press them apart from each other and against the junk-ring or cover and the piston-flange, substantially as and for the purposes set forth.

WILLIAM ROWAN.

In presence of—

FREDK. W. E. WHITE,

F. B. SIMS.
